STRAINER

Vincent Paul Bourne-Vanneck, New York, N. Y.

Application October 10, 1952, Serial No. 21,795

Term of patent 7 years

(Cl. D44—29)

To all whom it may concern:

Be it known that I, Vincent Paul Bourne-Vanneck, a subject of Great Britain, and a resident of New York, county of New York, and State of New York, have invented a new, original, and ornamental Design for a Strainer, of which the following is a specification, reference being had to the accompanying drawing, forming a part thereof:

Figure 1 is a top plan view of a strainer showing my new design;

Figure 2 is a side elevational view thereof;

Figure 3 is a transverse vertical sectional view thereof on the plane of the line 3—3 of Figure 1; and

Figure 4 is a bottom plan view thereof.

I claim:

The ornamental design for a strainer, as shown.

VINCENT PAUL BOURNE-VANNECK.
